APPARATUS FOR FIRING DEHYDRATING PLANTS AND FOR COOLING THE PRODUCT

Juan C. Byers, Kansas City, Mo., assignor to Butane Motor Fuel Company, Kansas City, Mo., a corporation of Missouri

Application March 14, 1949, Serial No. 81,313

16 Claims. (Cl. 263—1)

1

This invention has to do with the treatment of food products and particularly with the dehydration of such products, usually immediately after harvest thereof when the same has a high liquid content, for subsequent storage or packaging for use in a relatively dry condition.

It is well known by those skilled in the field of dehydration, particularly with respect to animal feeds such as alfalfa and other leguminous products, that the conventional procedure of heating the crop to remove its water content results in subsequent storage of the finished product in a heated condition with a consequent loss in food value, particularly its carotene and vitamin A content while such product is so stored, which losses are, to an appreciable extent, caused by the product remaining in such heated condition prior to use.

It is one of the most important objects of this invention therefore, to provide apparatus for use by and in connection with a conventional dehydrating plant capable of automatically and inexpensively lowering the temperature of the finished product, prior to storage or packaging thereof, to the extent necessary to cause the finished product to retain its carotene and vitamin A content and other food values until consumed, depending of course, on storage conditions used.

Another important object of the present invention is to provide apparatus capable of accomplishing the results just above mentioned and also operable to utilize liquid, combustible hydrocarbons in firing a vaporous gas burning furnace forming a part of the dehydrating plant, the apparatus being so formed and arranged as to include the necessary liquid vaporization step by use of heat emanating from the material itself, all to the end that the actual fuel consumption is reduced appreciably.

It is seen from the foregoing therefore, that it is the primary object of the present invention to provide apparatus capable of utilizing liquified petroleum gas for firing the furnace of a dehydrating plant and also for cooling the product that is produced by said plant, the apparatus including structure capable of using waste heat emanating from the product itself in vaporizing the liquid for use by the furnace and in so using such waste heat, cooling the product prior to storage thereof.

A further object of the present invention is to provide apparatus including a vaporizer for converting liquid petroleum gas to a vaporized state for use by the furnace of the dehydrating plant, the vaporizer itself being heated, as the

liquid is released thereto under pressure for augmenting vaporization, by the product itself.

A still further object of the present invention is to provide apparatus as above set forth wherein a coolant is continuously circulated around the aforesaid vaporizer in heat exchange relationship thereto and wherein the heated product emanating from the dehydrator is brought into heat exchange relationship with such coolant, all to the end that the product itself is automatically cooled and the vaporizer is automatically heated to induce vaporization of the liquid fuel.

Other important objects will be made clear or become apparent as the following specification progresses, reference being had to the accompanying drawing, wherein:

The single figure shows diagrammatically a dehydrating plant having apparatus for utilizing liquified petroleum gas for firing the furnace thereof and for cooling the product produced by the plant itself, all made in accordance with my present invention.

Various means have heretofore been provided for cooling food products emanating from a dehydrating plant to a sufficient degree to insure retention of carotene and vitamin A content in the finished product, which include refrigerating structures having means for bringing the heated product into heat exchange relationship with a coolant. Virtually all of such previously disclosed devices have been impractical however, particularly in the dehydration of feed for farm animals such as alfalfa and the like, because of the fact that such a large volume of the feed is handled by the plant, resulting in considerable expense in the operation of the refrigerating structure itself.

It is also appreciated that liquified petroleum gas and other combustible hydrocarbons, have heretofore been used in dehydrating plants for firing the furnace thereof and that vaporizers have been used to convert such liquid to a gaseous form. However, here again to attain complete vaporization of the liquid, a great amount of fuel is consumed to operate the vaporizer, with the resultant additional expense.

It will be appreciated after perusal of the following specification, that I have combined the product cooling structure with the means for vaporizing the fuel itself, all capable of reducing fuel consumption drastically and cooling the finished product to relatively low temperatures if desired.

In the drawing, there is illustrated a conventional dehydrating plant which includes an elong-

gated, cylindrical drum 10, mounted on rollers 12 for rotation on a substantially horizontal axis and motivated by any suitable prime mover, not shown. It is appreciated that the particular type of dehydrator that is used is immaterial to the present invention but in all plants of this character, there is provided means such as a furnace 14 for applying heat to the liquid containing product to be dehydrated. Such heat is directed into the rotating drum 10 through the medium of a conduit 16 and there is also provided an inlet opening in the drum not shown, for introducing the product itself thereinto. Drum 10 is also obviously provided with an outlet opening for the dehydrated product that empties into a suitable blower 18 that forces the heated product upwardly through a conduit 20. Conduit 20 empties into a cyclone separator 22 and the product moves by force of gravity through the open bottom of separator 22, through a conduit 24 and into another blower 26. The product is again conveyed upwardly by blower 26 through a conduit 28 for dumping into a second cyclone separator 30, whereupon the product passes by force of gravity outwardly from the separator 30 through a pipe 32 and into a conventional grinder or hammer mill 34.

Hammer mill 34 is equipped with means for forcing the ground product upwardly through a pipe 36 and into a collector 38 where the product falls by force of gravity downwardly through a conduit 40 and into a waste heat boiler, broadly designated by the numeral 42 and hereinafter to be more fully described.

The structure just above described is for illustrative purposes only and obviously, in some dehydrating plants more than two cyclone separators are used and oftentimes a plurality of hammer mills 34, as well as a like number of collectors 38, are provided. In other cases there is provided pellet forming apparatus and hammer mills are not used. Such multiplicity of parts has no bearing on the present invention and it will be appreciated upon understanding the principles hereof, that the same can be applied irrespective of the precise arrangement of the plant itself.

This invention contemplates the use of a liquid fuel for firing the furnace 14 such as a combustible hydrocarbon including butane or any other liquified petroleum gas. This liquid fuel is stored within a container 44 under pressure, which at times may approach 250 pounds per square inch. There is provided a heat exchanger broadly designated by the numeral 46 that includes a hollow tank 48 having therein the usual coils connected at the inlet end thereof with the fuel supply tank 44 by means of a pipe 50.

A shut-off valve 52 is interposed in the pipe 50 as is a pressure regulator 54 between valve 52 and heat exchanger 46. The outlet end of the coils within the heat exchanger 46 communicates with a conduit 56 that communicates directly with furnace 14 in the usual manner.

A liquid trap 58 is interposed in the line 56 together with a pressure regulator 60 next adjacent the furnace 14 and a control valve 62 is in the line 56 between trap 58 and the pressure regulator 60. Each of the cyclone separators 22 and 30 and the collector 38 is provided with a hollow closed chamber designated by the numerals 64, 66 and 68 respectively. These said chambers are formed by a double wall construction in the separators 22 and 30 and the

collector 38 as illustrated, taking the form of jackets 70, 72 and 74 respectively.

The waste heat boiler 42 includes a hollow container 76 having an inlet spout 78 at the uppermost end thereof, communicating with container 76 and disposed to receive the heated product emanating from the pipe 40.

The lowermost end of the hopper-like container 76 is provided with an outlet opening and the product within container 76 is moved through such outlet and into sacks or other containers or the vehicles for conveying the product to a point of storage, through use of an auger-type conveyor 80. Container 42 is completely covered by a jacket 82 defining a space 84 around the outermost walls of container 76. Container 76 also has mounted therein a hollow receptacle 86 in any suitable manner and in spaced relationship to all walls thereof.

A plurality of agitators 90 within the container 76, all disposed in spaced relationship to the walls of container 76 and to the hollow body 86, serve to agitate the product within the waste heat boiler 42 for purposes hereinafter to be made clear.

All of the compartments 64, 66, 68 and 84, as well as the hollow body 86, are in direct communication with the tank 48 of heat exchanger 46 through a conduit system shown in the drawing.

Tank 48 has an outlet conduit 92 provided with a branch 94 that communicates with the lowermost end of the compartment 64 of separator 22. A liquid coolant such as a brine, is contained within the tank 48 and within the conduits and compartments connected therewith, such coolant that passes into the branch 94 emptying into a surge tank 96 interposed in branch 94. A liquid pump 98 within branch 94 draws the liquid from tank 48 through line 92 and branch 94 for emptying into the compartment 64.

A second branch 100 has a surge tank 102 and a liquid pump 104 and connects directly with the lowermost end of compartment 66 of separator 30. A third branch 106 has a surge tank 108 and a liquid pump 110 and communicates with the compartment 84 of waste heat boiler 42 at the lowermost end thereof. The main outlet line 92 of heat exchanger 46 communicates with the lowermost end of the compartment 68 of collector 38 and has interposed therein a surge tank 112 and a pump 114.

Control valves 116, 118 and 120 are provided in the branches 94, 100 and 106 respectively and the main line 92 has a control valve 122 disposed between branch 106 and the surge tank 112. The tank 48 of the heat exchanger 46 is also provided with a main inlet line 124 that connects directly with the uppermost end of the compartment 84 of boiler 42. Branches 126, 128 and 130 provided with control valves 132, 134 and 136 respectively, interconnect the main inlet line 124 for tank 48 with the uppermost ends of the compartments 64, 66 and 68 respectively. Line 124 is also provided with a control valve 138 between the branch 130 and the boiler 42.

Branch 106 communicates directly with body 86 by a conduit 88, and body 86 empties directly into line 124 by a conduit 90.

It is clear from the foregoing, that with all of the valves 116, 118, 120, 122, 132, 134, 136 and 138 open and with all pumps 98, 104, 110 and 114 operating, the fluid within tank 48 in which the coils therein are immersed, will be

circulated outwardly as indicated by arrows through line 92 and its branches 94, 100, and 106. Such fluid will pass into the compartments 64, 66, 68, 84 and 86 and return to the tank 48 by way of line 124 and its branches 126, 128 and 130. The hot dehydrated material passing through the separators 22 and 30, collector 38 and boiler 42, will move into heat exchange relationship with the circulating brine and as such liquid brine emanates from the tank 48 in a cooled condition, the temperature of the product will consequently be lowered. As the circulating liquid coolant absorbs heat from the dehydrated material, its temperature will be raised and consequently the liquid passing into tank 48, by way of line 124, will have an appreciably higher temperature than its temperature as the same passes from the tank 48. This change of temperature of the coolant within the heat exchanger 46, is caused by the passage of the liquid fuel from the tank 44 under pressure into the coils within heat exchanger 46; the heated coolant entering tank 48 and traversing the coils therewithin will, through heat exchange relationship with the vaporizing fuel within such coils, augment vaporization of the liquid fuel and such vaporized gas will pass into the furnace 14 by way of line 56. Obviously, the temperature of the finished product at the time the same passes from compartment 76, depends on the length of time the product is subjected to the coolant and it may be found that boiler 42 is unnecessary and that the compartments 64, 66 and 68 will lower the temperature of the finished product sufficiently to suit the desires of the operator. However, by permitting the product to dwell within the container 76 prior to actual discharge through use of auger 80, it is possible to lower the temperature of the product to a relatively low degree and further, through use of the waste heat boiler 42, the vaporization of the liquid fuel emanating from container 44 will be more complete. It may be found therefore, that boiler 42 will be the only device necessary to accomplish the desired results. Further, such dwelling can be controlled by use of limit switches of conventional character (not shown) to regulate the speed of auger 80. Such switches may well be disposed in inlet 78 and controlled by the weight of the material therein.

Through the provision of the agitators 90 and through use of the hollow body 86 that is embedded within the material within container 76, it is possible to continuously keep the warm product in heat exchange relationship with the coolant in compartment 84 and thereby render the entire system more effective. Obviously, it will be necessary to insulate all of the lines leading from and to the heat exchanger 46 as well as the jackets 10, 12, 14 and 82. The choosing of such insulation, as well as the choice of pumps 98, 104, 110 and 114 will, to a great extent, determine the temperature of the finished product and the amount of complete fuel vaporization that takes place.

Another factor which determines to a great extent the temperature of the finished product and the amount of complete vaporization of the liquid fuel is the pressure at which such liquid fuel is introduced into the coils of heat exchanger 46. It is contemplated that sufficient pressure will exist in the tank 44 to lower the temperature of the finished product well below that necessary to maintain its vitamin A content and other food values during packaging and storing.

Through use of the pressure regulator 44, such temperature of the finished product can be controlled.

While the relationship between the extent to which the dehydrated product is subjected to the coolant, and the pressure under which the liquid fuel is introduced to the heat exchanger, will determine the extent of complete fuel vaporization and the temperature of the finished product, it is contemplated that if desired, the pressure of the liquid fuel as the same enters the heat exchanger 46, may be increased through use of a compressor 140. Compressor 140 may be of conventional character and is interposed within a by-pass 142, valved as at 144 and 146 and interconnecting line 56 with a branch pipe 148 that joins tank 44 and main line 56. Branch 148 is also provided with a valve 150 adjacent its connection with line 56. Through use of compressor 140, it is possible to increase the pressure of the liquid fuel, to further lower the temperature of the finished product as desired.

It is believed that it will be necessary, when using such compressor 140, to provide a condenser 152 that may be water cooled through inlet and outlet pipes 154 and 156 respectively. Lines 154 and 156 have connection with a source of coolant not shown, and may even be connected with the heat exchanger 46 if desired. Condenser 152 is joined with branch 148 through a by-pass conduit 158, and a valve 160 in branch 148 may be closed to force the liquid emanating from compressor 140 through condenser 152.

It is appreciated therefore, from the foregoing that the temperature of the finished product and the extent of complete vaporization of the liquid fuel is dependent on a large number of factors including the over-all size of the dehydrating plant itself. It is, therefore, difficult to specify any certain temperatures or pressures, but it is contemplated that with the proper choosing of heat exchanger 46, with an introduction of the liquid fuel into the coils of heat exchanger 46 at 60 degrees Fahrenheit and with a pressure of approximately 30 pounds per square inch, the coolant will emanate from tank 48 and pass into the conduit 92 at approximately 20° F. It is further anticipated that the coolant will re-enter the heat exchanger 46 at approximately 80° F. and that the finished product emanating from the container 76 will be lowered in temperature to approximately 30 to 40° F. Whether or not it will be necessary or desirable to lower the temperature of the product to such extent, will depend of course, upon the type of storage means for the product and whether or not the same is itself insulated or otherwise formed to maintain the lowered temperature in the product so that the latter does not again reheat and thereby lose its vitamin A content. However, a relatively low temperature in the finished product has no effect thereupon and since vaporization of the liquid fuel can be enhanced, such should be done to reduce fuel consumption to as low a point as possible.

It is appreciated from the foregoing that the entire structure forming the subject matter hereof is automatic and when placed in operation, will not only lower the temperature of the finished product to a desired point, but will result in a tremendous saving in fuel consumption. Not only will the furnace of the dehydrator work more efficiently to the end that more complete dehydration of the product occurs, but the dam-

aging effect of storing the product in a heated condition will be eliminated.

Another feature of the present invention that is extremely important in this field, lies in the manner in which fire hazards are reduced. It has been found that many fires have been and are occurring in storage bins for dehydrated alfalfa and the like because of the fact that the product is stored with a live spark therein which was created during the dehydration process itself. Oftentimes even the hammer mill that is used for grinding the dehydrated material, creates a spark and this said spark is carried through and deposited in the storage bins. As such spark smoulders and increases in size within the bin, internal combustion and other factors enter in and a damaging fire occurs.

Through use of the waste heat boiler 42 as formed with a closed container 76, such sparks will be smothered as the material dwells within container 76. The product itself will seal the uppermost end of the pipe 78 of boiler 42 and even when auger 80 is continuously operating, the material will remain in the container 76 sufficiently long to extinguish all sparks that may be in the material.

I claim:

1. Material treating structure comprising a container for material to be treated, said container having a gas burning furnace for heating said material as the same passes through the container; a pressurized liquid fuel source separate from said material; a closed passage connecting said fuel source with said furnace; and a combination fuel vaporizing and material cooling assembly comprising a continuous fluid coolant chamber, a portion of said passage extending through said chamber, and means for directing the heated material into heat exchange relationship with a portion of said chamber as the former emanates from said container.

2. Material treating structure comprising a container for material to be treated, said container having a gas burning furnace for heating said material as the same passes through the container; a pressurized liquid fuel source separate from said material; a closed passage connecting said fuel source with said furnace; and a combination fuel vaporizing and material cooling assembly comprising a continuous, liquid coolant chamber, a portion of said passage extending through said chamber in immersed relationship with the coolant in the latter, means for directing the heated material into heat exchange relationship with a portion of said chamber as the former emanates from said container, and means for continuously circulating said coolant in the chamber.

3. Material treating structure comprising a container for material to be treated, said container having a vaporized gas burning furnace for heating said material as the same passes through the container; a source of combustible liquified hydrocarbon under pressure separate from said material; a closed passage connecting said hydrocarbon source with said furnace; and a combination hydrocarbon vaporizing and material cooling assembly comprising a continuous liquid coolant chamber, a portion of said passage extending through said chamber in immersed relationship with the coolant in the latter, means for directing the heated material into heat exchange relationship with a portion of said chamber as the former emanates from said container, means for continuously circulating said coolant

in the chamber, and means for controlling the flow of hydrocarbon from said source thereof to said portion of the passage within the chamber.

4. Material treating structure comprising a container for material to be treated, said container having a vaporized gas burning furnace for heating said material as the same passes through the container; a source of liquified petroleum gas under pressure separate from said material; a closed passage connecting said liquified petroleum gas source with said furnace; and a combination liquified petroleum gas vaporizing and material cooling assembly comprising a continuous liquid coolant chamber, a portion of said passage extending through said chamber in immersed relationship with the coolant in the latter, means for directing the heated material into heat exchange relationship with a portion of said chamber as the former emanates from said container, means for continuously circulating said coolant in the chamber, means for controlling the flow of liquified petroleum gas from said source thereof to said portion of the passage within the chamber, and means for controlling the flow of vaporized gas from said portion of the passage to the furnace.

5. Material treating structure comprising a container for material to be treated, said container having a vaporized gas burning furnace for heating said material as the same passes through the container; a source of liquified petroleum gas under pressure separate from said material; a closed passage connecting said liquified petroleum gas source with said furnace; a heat exchanger having a vaporizer interposed within said passage for receiving the liquified petroleum gas, and a chamber enclosing said vaporizer, said chamber being adapted to contain a liquid coolant for immersing said vaporizer; at least one hollow compartment having connection with said chamber; means for circulating said coolant through the compartment and chamber; and means for directing the heated material emanating from the container against the outer surfaces of said compartment.

6. Material treating structure comprising a dehydrator for material to be treated, said dehydrator having a vaporized gas burning furnace for heating said material as the same passes through the dehydrator; a source of liquified petroleum gas under pressure; a closed passage connecting said liquified petroleum gas source with said furnace; a heat exchanger having a vaporizer interposed within said passage for receiving the liquified petroleum gas, and a chamber enclosing said vaporizer, said chamber being adapted to contain a liquid coolant for immersing said vaporizer; at least one hollow compartment having connection with said chamber; means for circulating said coolant through the compartment and chamber; means for directing the heated material emanating from the dehydrator against the outer surfaces of said compartment; and means for controlling the pressure of said liquified petroleum gas as the same passes into the vaporizer whereby to control the temperature of said coolant.

7. Material treating structure comprising a dehydrator for material to be treated, said dehydrator having a vaporized gas burning furnace for heating said material as the same passes through the dehydrator; a source of liquified petroleum gas; means for compressing said liquified petroleum gas; a heat exchanger having a vaporizer and a closed chamber surrounding said

vaporizer, said chamber being adapted to contain a liquid coolant for immersing said vaporizer; means for directing the compressed liquified petroleum gas into the vaporizer; means connecting said vaporizer with said furnace; at least one hollow compartment having connection with said chamber; means for circulating said coolant through the compartment and chamber; means for directing the heated material emanating from the dehydrator against the outer surfaces of said compartment; and means for controlling the pressure of said liquified petroleum gas as the same passes into the vaporizer whereby to control the temperature of said coolant.

8. Material treating structure comprising a dehydrator for material to be treated, said dehydrator having a vaporized gas burning furnace for heating said material as the same passes through the dehydrator; a source of liquified petroleum gas under pressure; a closed passage connecting said liquified petroleum gas source with said furnace; a heat exchanger having a vaporizer interposed within said passage for receiving the liquified petroleum gas, and a chamber enclosing said vaporizer, said chamber being adapted to contain a liquid coolant for immersing said vaporizer; at least one hollow compartment having connection with said chamber; means for circulating said coolant through the compartment and chamber; means for directing the heated material emanating from the dehydrator against the outer surfaces of said compartment; and auxiliary means for selectively increasing the pressure of said liquified petroleum gas prior to passage thereof into said vaporizer whereby to lower the temperature of said coolant desired amounts.

9. In a material treating assembly having apparatus for heating the material as the same is treated, and including a furnace adapted to burn vaporized gas; means for utilizing the heat emanating from said material after the same passes from said apparatus to vaporize a liquified petroleum gas under pressure separate from said material for use by said furnace, said means comprising a heat exchanger having a chamber adapted to contain a circulating liquid coolant and a vaporizer immersed in said coolant for receiving said pressurized liquified gas; a passage for connecting said vaporizer with said furnace; and structure for directing the heated material from said apparatus into heat exchange relationship with a portion of said chamber.

10. In a material treating assembly having apparatus for heating the material as the same is treated, and including a furnace adapted to burn vaporized gas; a structure for automatically converting liquified petroleum gas under pressure separate from said material to gas vapor for use by said furnace and simultaneously refrigerating the heated material emanating from said apparatus, said structure comprising a heat exchanger having a chamber adapted to contain a circulating liquid coolant and a vaporizer immersed in said coolant for receiving said pressurized petroleum gas; a passage for connecting said vaporizer with said furnace; a jacketed passage for receiving said heated material as the same emanates from said apparatus; and means for placing said jacket into communication with the chamber.

11. In a material treating assembly having apparatus for heating the material as the same is treated, and including a furnace adapted to burn vaporized gas; structure for automatically converting liquified petroleum gas under pressure

10

separate from said material to gas vapor for use by said furnace and simultaneously refrigerating the heated material emanating from said apparatus, said structure comprising a heat exchanger having a chamber adapted to contain a liquid coolant and a vaporizer immersed in said coolant for receiving said pressurized petroleum gas; a passage for connecting said vaporizer with said furnace; a container for receiving the heated material from said apparatus, said container having a closed compartment therearound; means placing said compartment into communication with said chamber; and mechanism for circulating said coolant through the compartment and the chamber.

12. In a material treating assembly having apparatus for heating the material as the same is treated, and including a furnace adapted to burn vaporized gas; structure for automatically converting liquified petroleum gas under pressure to gas vapor for use by said furnace and simultaneously refrigerating the heated material emanating from said apparatus, said structure comprising a heat exchanger having a chamber adapted to contain a liquid coolant and a vaporizer immersed in said coolant for receiving said pressurized petroleum gas; a passage for connecting said vaporizer with said furnace; a container for receiving the heated material from said apparatus, said container having a closed compartment therearound; means placing said compartment into communication with said chamber; mechanism for circulating said coolant through the compartment and the chamber; and means for agitating said material in the container.

13. In a material treating assembly having apparatus for heating the material as the same is treated, and including a furnace adapted to burn vaporized gas; structure for automatically converting liquified petroleum gas under pressure to gas vapor for use by said furnace and simultaneously refrigerating the heated material emanating from said apparatus, said structure comprising a heat exchanger having a chamber adapted to contain a liquid coolant and a vaporizer immersed in said coolant for receiving said pressurized petroleum gas; a passage for connecting said vaporizer with said furnace; a container for receiving the heated material from said apparatus, said container having a closed compartment therearound; means placing said compartment into communication with said chamber; mechanism for circulating said coolant through the compartment and the chamber; and a closed, hollow body in the container imbedded within the material therein and having means for placing the same into communication with said chamber.

14. In a material treating assembly having a dehydrator for the material being treated provided with a material heating furnace adapted to burn vaporized gas, at least one separator for receiving the heated dehydrated material from the dehydrator, pulverizing means disposed to receive the material from the separator, and means for collecting the pulverized material; in combination, material cooling means including a hollow compartment for said separator and said collector respectively, each disposed in surrounding relationship to the flow of material, a hollow chamber adapted to contain a liquid coolant and communicating with said compartments, and means for circulating said coolant through the chamber and the compartments; and structure for converting liquified petroleum gas under pres-

75

11

sure into vaporized gas for use by said furnace, said structure including a vaporizer for receiving said liquified gas through pressure and adapted for connection with the furnace, said vaporizer being disposed within said chamber in immersed relationship with the coolant, whereby the material is cooled and the liquified petroleum gas is simultaneously vaporized as the coolant is circulated, as the material passes through the separator and collector, and as the liquified gas passes to the vaporizer under pressure.

15. In a material treating assembly having a dehydrator for the material being treated provided with a material heating furnace adapted to burn vaporized gas, at least one separator for receiving the heated dehydrated material from the dehydrator, pulverizing means disposed to receive the material from the separator, means for collecting the pulverized material, and a container for receiving the material from said collector; in combination, material cooling means including a hollow compartment for said separator, said collector and said container respectively, each disposed in surrounding relationship to the flow of material, a hollow chamber adapted to contain a liquid coolant and communicating with said compartments, and means for circulating said coolant through the chamber and the compartments; structure for converting liquified petroleum gas under pressure into vaporized gas for use by said furnace, said structure including a vaporizer for receiving said liquified gas through pressure and adapted for connection with the

12

furnace, said vaporizer being disposed within said chamber in immersed relationship with the coolant, whereby the material is cooled and the liquified petroleum gas is simultaneously vaporized as the coolant is circulated, as the material passes through the separator and collector, and as the liquified gas passes to the vaporizer under pressure; and means for agitating said material within the container to increase heat absorption by said coolant from the material.

16. Apparatus for utilizing liquified petroleum gas for firing a furnace of a dehydrating plant adapted to burn vaporized gas and for cooling the product produced by said plant, said apparatus comprising a heat exchanger having a chamber adapted to contain a coolant and a vaporizer within the chamber; means for directing liquified petroleum gas separate from said product into the vaporizer under pressure; structure for moving the product emanating from said plant into heat exchange relationship with a portion of said chamber; and means for feeding vaporized gas from said vaporizer to said furnace.
